CLAIM

The ornamental design for a body sculpting garment as shown and described.

DESCRIPTION

FIG. 1 is a front view of a body sculpting garment according to a first embodiment of the design;

FIG. 2 is a rear view of FIG. 1;

FIG. 3 is a right side view of FIG. 1;

FIG. 4 is a front view of a body sculpting garment according to a second embodiment of the design;

FIG. 5 is a front view of FIG. 4 showing an alternative position of the zipper;

FIG. 6 is a rear view of FIG. 4;

FIG. 7 is a right side view of FIG. 4;

FIG. 8 is a right side view of FIG. 4 showing an alternative position of the zipper;

FIG. 9 is a front view of a body sculpting garment according to a third embodiment of the design;

FIG. 10 is a front view of FIG. 9 showing an alternative position of the zipper;

FIG. 11 is a rear view of FIG. 9;

FIG. 12 is a right side view of FIG. 9;

FIG. 13 is a right side view of FIG. 9 showing an alternative position of the zipper;

FIG. 14 is a front view of a body sculpting garment according to a fourth embodiment of the design;

FIG. 15 is a rear view of FIG. 14; and,

FIG. 16 is a right side view of FIG. 14.

The broken lines depicting the humanoid figure are for illustrative purposes only and form no part of the claimed
